UNITED STATES PATENT OFFICE.

WALTER H. SMITH, OF WILKINSBURG, PENNSYLVANIA, ASSIGNOR TO WESTINGHOUSE ELECTRIC & MANUFACTURING COMPANY, A CORPORATION OF PENNSYLVANIA.

RELAY.

1,312,757.

Specification of Letters Patent. Patented Aug. 12, 1919.

Application filed June 13, 1917. Serial No. 174,434.

To all whom it may concern:

Be it known that I, WALTER H. SMITH, a citizen of the United States, and a resident of Wilkinsburg, in the county of Allegheny and State of Pennsylvania, have invented a new and useful Improvement in Relays, of which the following is a specification.

My invention relates to relays and particularly to relays for protecting the motor circuits of electrically operated vehicles.

One object of my invention is to provide a relay that shall have means for controlling the closing of the main line switch of a circuit to be protected when the trolley is in position; for opening the switch when an overload or short circuit obtains on the circuit; for opening the switch when the trolley or current collector jumps from the trolley conductor or crosses a break therein and for locking the relay in its inoperative position after it has functioned to open the switch upon the occurrence of an overload or short circuit.

Another object of my invention is to provide a relay of the above indicated character that shall be inexpensive to construct, compact in size and efficient and reliable in its operation.

In practising my invention, I provide a combined line and overload relay for the motor circuit of an electric locomotive having coöperating contact members for controlling the circuit of the actuating winding of the main line switch. Electromagnetic means is provided to effect closure of the contact members when the trolley is in position. Other electromagnetic means is provided to effect the opening of the contact members when an overload or an excess current obtains on the motor circuit, and means is provided for holding the contact members in their open position when opened by reason of an overload or a short circuit. Means, such as a spring, is provided for opening the contact members when the trolley jumps from the trolley conductor or when it crosses a break in the same. Such a device obviates the necessity of employing separate line, overload and resetting relays and has the advantage that economy of space and material, so essential in electrically operated vehicles, may be obtained.

Figure 1 of the accompanying drawings is a view, partially in elevation and partially in section, of a relay embodying my inven-

tion, illustrating its connection to a circuit to be protected, and Fig. 2 is a front elevational view of a portion of a modified form of relay embodying my invention.

A trolley conductor 1 is operatively connected, through a trolley or current-carrying device 2, a relay 3, a hand-operated switch 4, a controller 5, an electrically operated switch 6 and a motor 7 to ground.

The relay 3 comprises three independent stationary magnetizable core members 8, 9 and 10, a movable magnetizable core member 11 and two movable magnetizable members 12 and 13. A winding 14, one terminal of which is connected to the collector device 2 through a conductor 15 and the other terminal of which is connected to ground through a conductor 16, is adapted to coöperate with the core members 8 and 11 for the purpose of actuating the movable core member 11 when the trolley or collector 2 is in position and when current traverses the trolley conductor 1.

The movable core member 11 is mounted on a rod 17 that extends through the core members 8 and 9 and upon which is also mounted a bridging contact member 18 that is adapted to coöperate with stationary contact members 19 and 20. The bridging contact member 18 is resiliently connected to the rod 17 by a spring 21, and a spring 22 is disposed between a stationary member 23 and a shoulder 24 on the rod 17 for the purpose of holding the bridging contact member 18 and, consequently, the rod 17, in the position shown in the drawing when the winding 14 is not energized.

The movable magnetizable member 12 is pivotally mounted on a pin 25 and is adapted to be moved into engagement with the stationary core member 9 when a predetermined current traverses a winding 26 that is disposed around the core member 9. An adjusting screw 43 is provided for adjusting the initial setting of the member 12, and a calibration plate 44 is provided for indicating the setting of the same.

A winding 27 is disposed around the stationary core member 10, one of the terminals of which is connected to the conductor 16 and the other terminal of which is connected to the stationary contact member 28 of the switch 4. The movable contact member 29 of the switch 4 is connected to the conductor 15 and the other stationary contact member 110.

30 of the said switch is connected to one terminal of the controller 5 the other terminal of which is connected to the stationary contact member 19 of the relay 3. The movable magnetizable member 13 is pivotally mounted on a pin 31 and is provided with a latch device 32 that is adapted to engage a projection 33 on the member 12 for the purpose of holding the said member in its actuated position until the winding 27 is energized by reason of the manipulation of the switch 4.

10 The winding 26 is operatively connected, at one of its terminals, to the conductor 15 and, at its other terminal, to the stationary contact member 34 of the switch 6. The other stationary contact member 35 of the switch 6 is connected to one terminal of a resistor 36 the other terminal of which is connected to one terminal of the motor 7. The other terminal of the motor 7 is connected, through a reversing switch 37 and the field winding 38 of the motor, to ground.

20 The controller 5 is adapted to control the closure of a plurality of switches 39 that are connected across portions of the resistor 36 for the purpose of controlling the current through the motor 7 and, consequently, its speed. The switch 6 comprises a movable bridging member 40, a magnetizable core member 41, a winding 42 and the stationary contact members 34 and 35. One terminal of the winding 42 is connected to the stationary contact member 20 of the relay 3 35 and the other terminal of said winding is connected to the conductor 16.

When the current-collecting device or trolley 2 is disconnected from the trolley conductor 1, the spring 22 will hold the bridging contact member 18 in the position shown in the drawing. However, when the trolley 2 is placed in contact with the trolley conductor 1 and current traverses the said conductor, the winding 14 will be energized to move the core member 11 downwardly to such position that the bridging contact member 18 engages the stationary contact members 19 and 20. When the contact members 18, 19 and 20 are engaged, the movable contact member 29 of the switch 4 is in engagement with its stationary contact member 30 and the controller 5 is in the correct position, a circuit is completed from the conductor 1 through the controller 5 and the winding 42 of the switch 6. This will cause the bridging contact member 40 to engage the stationary contact members 34 and 35, and the motor 7 will be supplied with current which may be controlled by manipulating the controller 5.

60 If a predetermined excessive load is taken by the motor 7, sufficient current will traverse the winding 26 to attract the movable magnetizable member 12. When the member 12 is moved into engagement with the sta-

tionary core member 9, it will engage the lower end of the rod 17 and effect disengagement of the bridging contact member 18 and stationary contact members 19 and 20. This will open the circuit of the actuating winding 42 of the switch 6 and disconnect the motor 7 from the circuit. When the member 12 engages the core member 9, its projection 33 will be engaged by the latch member 32 to hold the contact members 18, 19 and 20 in their open positions. If it is desired to reset the device in order that, upon the cessation of the overload, the device will refunction, the movable contact member 29 of the switch 4 is moved into engagement with the stationary contact member 28. This completes a circuit from the conductor 15 through the winding 27 to the conductor 16 which causes the movable magnetizable member 13 to be attracted to release the movable member 12 for the purpose of unlocking the rod 17.

70 After the winding 14 has been energized and the contact members 18, 19 and 20 are in engagement, if the trolley 2 jumps from the trolley conductor 1 or crosses a break therein, the winding 14 will be deenergized and the spring 22 will move the rod 17 upwardly to effect disengagement of the contact members 18, 19 and 20 and thereby open the switch 6, as hereinbefore set forth.

75 The force exerted by the member 12 must overcome the pull of the winding 14 on the member 11, but, in view of the fact that the overload setting of the winding 26 may be of such value that insufficient force is imparted to the member 12 to overcome the pull of the winding 14, means may be provided, as shown in Fig. 2 of the drawings, for open circuiting the winding 14 as soon as the member 12 is actuated. That is, a stationary contact member 45 is substituted for the adjusting screw 43 shown in Fig. 1 of the drawings and a resiliently mounted contact member 46 is so mounted that it is actuated by an adjusting screw 47 which is mounted in a projection 48 on the member 12.

80 In the modified structure just mentioned, when the winding 27 is energized, the member 12 is permitted to assume such position that the contact members 45 and 46 are in engagement and the circuit through the winding 14 is completed. By such an arrangement, the force exerted by the member 12 need not be of such value as to overcome the pull of the winding 14 on the member 11 because, as soon as the member 12 is actuated, the circuit of the winding 14 is opened at the contact members 45 and 46.

85 I, of course, do not limit my invention to the particular structure illustrated, as it may be variously modified without departing from the spirit and scope of the invention as set forth in the appended claims.

I claim as my invention:

1. A relay for an electric circuit comprising two relatively movable magnetizable members, a potential winding for actuating one of the members under predetermined normal conditions in the circuit, a current winding for actuating the other movable member when an overload traverses the circuit, and means actuated by the second movable member for opposing the operation of the other movable member.
2. A relay for an electric circuit comprising two relatively movable magnetizable members, a winding for actuating one of the movable members under predetermined normal conditions in the circuit, a second winding for actuating the other movable member when an overload traverses the circuit, and means actuated by the second movable member for opposing the operation of the other movable member.
3. A relay for an electric circuit comprising two relatively movable magnetizable members, means for actuating one of the members under predetermined normal conditions in the circuit, a second means for actuating the other movable member when an overload traverses the circuit, and means actuated by the second movable member for opposing the operation of the other movable member.
4. A relay device comprising coöperating contact members, means for effecting engagement of the contact members when the relay is connected in circuit under normal conditions, means for positively locking the contact members in their open position under predetermined conditions and means for unlocking the contact members.
5. A relay device for an electric circuit comprising coöperating contact members, spring-restrained means for effecting engagement of the contact members under normal conditions in the circuit, means for positively locking the contact members in their open position when an overload traverses the circuit and electromagnetic means for unlocking the contact members.
6. A relay for an electric circuit comprising two relatively movable magnetizable members, stationary contact members, movable contact members operatively connected to one of the movable magnetizable members, means for actuating one of the movable members to effect engagement of the contact members under normal conditions in the circuit, means for actuating the other movable member to disengage the contact members when an overload traverses the circuit and latching means for positively holding the second movable member in its actuated position after the removal of the overload.
7. A relay for an electric circuit comprising two relatively movable magnetizable members, means for actuating one of the members under predetermined normal conditions in the circuit, a second means for actuating the other movable member when an overload traverses the circuit, means actuated by the second movable member for opposing the operation of the other movable member, and means for positively locking the second movable member in its actuated position.

In testimony whereof, I have hereunto subscribed my name this 31st day of May 1917.

WALTER H. SMITH.
